UNITED STATES PATENT OFFICE.

PETER J. DAWKINS, OF BROOKLYN, NEW YORK.

DESIGN FOR TYPE.

SPECIFICATION forming part of Design No. 15,767, dated February 3, 1885.

Application filed December 23, 1884. Term of patent 7 years.

To all whom it may concern:

Be it known that I, PETER J. DAWKINS, of Brooklyn, Kings county, New York, have invented and produced a new and original Design for a Font of Printing-Type, of which the following is a specification.

The nature of my design is clearly shown in the accompanying typographic impression, to which reference is made; and it consists of an unshaded letter having the heavy arched terminations, as shown in the A, F, H, I, K, L, M, N, T, V, W, X, and Y, at the top and bottom of the up-and-down portions, in the central line of the E, the lower right-hand termination of the G, the upper portion of the

J and U, the lower portions of the P and R, while the configuration of the B, C, D, S, and Q corresponds as nearly as possible to the character of the design. In the dollar-mark and the numerals—notably the 1, 4, and 7—the character of the design is preserved.

Having now set forth my invention, I claim as new—

The design for a font of printing-type, as shown and described.

PETER J. DAWKINS.

WILLIAM V. H. HICKS,
